(57) **CLAIM**

The ornamental design for a rotatable camera mobile phone, as shown and described.

DESCRIPTION

FIG. 1 is a perspective view of the front, bottom and right side of a rotatable camera mobile phone showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a perspective view thereof with the camera in the rotated position; and,

FIG. 9 is a perspective view thereof with the camera in the rotated position.

The push buttons are shown in broken lines for illustrative purposes only, and forms no part of the claimed design.
